WILLIAM ELY STANFORD AND ELMA LETTIE STANFORD, OF CALEXICO, CALIFORNIA.

VEHICLE SPRING.

Application filed May 18, 1922. Serial No. 561,889.

To all whom it may concern:

Be it known that we, WILLIAM ELY STANFORD and ELMA LETTIE STANFORD, citizens of the United States, and residents, respectively, of Calexico, county of Imperial, and State of California, have invented a new and useful Vehicle Spring, of which the following is a specification.

The present invention relates to improvements in vehicle springs and its particular object is to provide springs adapted to be used for any kind of vehicle and particularly adapted to absorb shocks received by the vehicle while traveling on a rough road.

The particular principle involved is that of providing a plurality of co-acting springs called into play successively so that only certain main springs are used while a normal load is carried, while other springs which remain idle under a normal load are called upon when shocks are received and quickly and effectively absorb the same. Springs of this kind offer many advantages and we claim that if our springs are arranged under a vehicle in the proper manner they will allow the same to travel on a rough road with almost the same facility and at almost the same speed as on a paved road.

It is further proposed to arrange the springs that are normally idle in such a manner that they are stretched to different degrees of tension so that only the heaviest shocks will call into play all of the springs employed, while lighter shocks will render active only a portion of the same. This feature exercises an equalizing effect and will cause the shocks received by the axles of the vehicle to be transmitted to the body gradually and with a certain uniform intensity since the heavier shocks have to overcome greater resistance before they affect the body. Further advantages of our springs will appear as the description proceeds.

With these objects in mind we have illustrated the preferred form of our invention in the accompanying drawings, in which Figure 1 shows a side elevation of one of our spring arrangements; Figure 2 a top plan view of the same; Figure 3 a cross section along the line 3-3 of Figure 2; Figure 4 a side elevation of a modified form of spring arrangement; Figure 5 a top plan view of said modified form; Figure 6 a side

elevation of a further modification; Figure 55 7 a top plan view of the same; Figure 8 a side elevation of another modification; Figure 9 a top plan view of the same, and Figure 10 a cross section through the same along line 10-10 of Figure 8. The idea expressed in our invention has thus been illustrated in four different modifications, but it should be understood that various other slight changes or alterations may be made within the scope of the claims hereto attached without departing from the spirit of the invention.

Referring particularly to Figure 1, it will be seen that a rigid frame (1) is supported on an axle (2) by means of clamps (3), a retaining plate (4) and nuts (6). The particular means of fastening the frame to the axle are of no consequence for the purpose of this description and any suitable means may be employed. As will be seen the frame rests on the axle on edge or in a vertical plane and presents in its essential features a lower frame member (7) resting on the axle, an upper frame member (8) and two lateral frame members (9) and (11). From the upper frame member (8) are pivotally supported two links (12) and (13) and support with their free ends the main spring (14). The latter comprises one principal leaf (16) and a plurality of shorter leaves (17) decreasing in size symmetrically. The leaves are not in direct contact with each other but have small spacing plates (18) interposed between the same so that ordinarily the principal leaf (16) is the only one in this arrangement that supports the load and the other leaves are not called into action until a shock is received by the axle, in which case the other leaves will be successively engaged, each doing its share to absorb and deaden the shock so that very little is finally transmitted to the body. Additional leaves (19) are provided underneath the principal leaf (16) and assist in carrying the normal load as well as in checking the rebound.

The spring thus far described is connected with the body of the vehicle through the block (21) shown in Figure 3 as consisting of an upper portion (22) and a lower portion (23) joined by means of bolts (24) penetrating registering flanges (26). In the upper block member (22) is se-

cured a supporting member (28) by means of screws (29) or in any other suitable manner, which latter carries the plate (31) adapted to receive the body of the vehicle.

5 It will be seen from Figure 1 that a large plurality of other springs is provided to assist in absorbing the shocks. These springs may be arranged in various ways and we do not wish to be understood as confining ourselves to the special arrangement shown in 10 any of the illustrations. In designing this arrangement our principal object was to provide springs having different degrees of tension and strength so that all of the 15 springs would not be rendered active simultaneously, but some might remain idle while others were being used. In Figure 1, for instance, the diagonal springs (32) connecting the block with the upper and lower 20 frame members respectively might be balanced to assist the main spring in carrying the normal load. The springs (33) passing through the block through holes (34) tapering from the center in both directions 25 would be somewhat lighter and would not be called into play unless a shock had been received by the axle. The springs (36) would be still lighter and would not perform any function unless a severe jolt had 30 been received by the axle. Any number of steps and graduations might be arranged in this manner and the execution of this idea may be effected in many various ways.

35 The modifications shown in Figures 4 and 5 while based on the same principal offer slight changes in the manner in which it may be attached to the car. In this modification the axle (37) serves as a part of the 40 frame and two lateral frame members (38) and (39) are secured to the axle directly by means of clamps (41) or in any other suitable manner, while the upper frame member is dispensed with so that the block 45 (42) resting on the main spring (43) and being additionally supported by the springs (44) and (46) may have the body of the vehicle directly secured thereon. A further modification is shown in the fact that the 50 links (12) and (13) of Figure 1 have been replaced by springs (47) and (48), which would allow the body to sway back and forth over the axle and to assume a rocking motion similar to that of a boat on the 55 water. The modification shown in Figures 6 and 7 is designed principally to be used to stretch across the whole length of the vehicle, (51) representing the front axle and (52) the rear axle. Thus only lateral members (53) and (54) are employed for the frame. Instead of a straight main spring a 60 semi-elliptical spring (56) is used and for its support we employ a plurality of links (57) corresponding in their affect very much with the springs (47) and (48) shown

in Figure 4. A block (58) rests on the spring and supports a plate (59) on which the body of the vehicle may be placed.

The modification shown in Figures 8, 9 and 10 offers new features in the form of 70 the frame (61), which comprises the lower member (62) and two lateral members (63) and (64), and in the means for supporting the main spring (66) which include a plurality of links (67) allowing of a swaying 75 backward and forward of the body of the car. The auxiliary springs (68), (69), (71) and (72) are carried through suitable perforations (74) within the block (73). 80

We claim:

1. Spring mounting means for a vehicle comprising a rigid frame supported on a vehicle axle in a vertical plane, a main spring pivotally supported inside of the frame having a block associated therewith with means thereon for supporting the vehicle body, and a plurality of auxiliary springs between the frame and the block, said springs being stretched to different degrees of tension so as to be called into play successively. 85

2. Spring mounting means for a vehicle comprising a rigid frame supported on a vehicle axle in a vertical plane, a main leaf spring pivotally supported inside of the frame having a block associated therewith with means thereon for supporting the vehicle body and a plurality of auxiliary springs extending through the block in 90 transverse direction. 95

3. Spring mounting means for a vehicle comprising a rigid frame supported on a vehicle axle in a vertical plane, a main leaf spring pivotally supported inside of the frame having a block associated therewith with means thereon for supporting the vehicle body and a plurality of auxiliary springs extending through the block in transverse direction, the transverse holes in the block allowing the springs to pass therethrough being tapered toward either end for facilitating endwise play of the springs. 100

4. Spring mounting means for a vehicle comprising a rigid frame supported on a vehicle axle in a vertical plane, a main leaf spring pivotally supported inside of the frame having a block associated therewith with means thereon for supporting the vehicle body and a plurality of transversely arranged auxiliary springs supporting the block, some of the latter springs extending from the sides of the block and others extending through the block with freedom of endwise play. 115

5. Spring mounting means for a vehicle comprising a rigid frame supported on a vehicle axle in a vertical plane, a block having means thereon for supporting the vehicle body and transverse springs supported 120 125 130

in the frame extending through the block for supporting the same.

6. Spring mounting means for a vehicle comprising a rigid frame supported on a vehicle axle in a vertical plane, a block having means thereon for supporting the vehicle body and transverse springs supported in the frame extending through the

block for supporting the same, the holes in the block allowing the springs to pass therethrough being tapered toward either end so as to allow of endwise play of the springs within the block. 10
